UNITED STATES PATENT OFFICE.

ALEXANDRE LAMBLIN, OF PARIS, FRANCE.

DIAPHRAGM PUMP.

Original application filed October 5, 1925, Serial No. 60,436, and in France December 5, 1924. Divided and this application filed July 20, 1926. Serial No. 123,620.

The present invention has reference to various improvements applied to feed pumps and in particular to pumps intended for feeding petrol to explosion motor carburetors. These improvements have for their object to render the operation of the pump safer and more efficient. The present application is a division of application Serial Number 60,436 filed October 5, 1925.

10 A diaphragm pump according to the invention, is characterized in particular by an auxiliary diaphragm, arranged in the chamber which forms the pump body and in which the main diaphragm moves, said auxiliary diaphragm constituting a wall which is rigid and permits the working of the diaphragm pump as long as the pressure in the pump body remains below a determined value, whilst said auxiliary diaphragm yields and 20 follows the main diaphragm in its displacement as soon as the pressure becomes excessive in the pump body. In this manner any variation of volume in said pump body is prevented and working of the pump arrested.

25 The preferred form of the invention is shown in the accompanying drawings in which:—

Figure 1 is a plan view of the pump;
Figure 2 is a partial section of said pump

30 through a vertical plane corresponding to the line 2—2 of Figure 1.

Figure 3 is a partial section of the pump corresponding to the line 3—3, of Figure 2.

The pump illustrated in Figures 1—3 is 35 formed by the combination of two diaphragm pumps 1 and 2 joined together and symmetrically arranged with reference to the plane $x-y$.

Each of said pumps consists of a pump body 3 and a casing 4 containing the working mechanism, these two elements being 40 separated from each other by three deformable diaphragms 5 of vulcanized fibre and of considerable thickness, kept at a suitable distance apart from one another and separated by two diaphragms 5¹ forming soft and impermeable joints.

The edges of each deformable diaphragm 5 and of each softer diaphragm 5¹ are tightly held between the edges of the pump body 3 and of the casing 4, and form an impermeable joint there.

The pump body 3, upon the vertical axis $z-z'$, is provided with a petrol filter and

valves. The filter consists of an inlet petrol tube 6 with lateral orifices 7. Such tube is screwed in the pump body properly so called and to its upper extremity is applied a sheet of filtering material 10, such as chamois leather, metallic gauge, etc. the lower edge 60 of which is tightened by a ring 11 on to the periphery of the tube.

The suction valve 12 and the delivery valve 13 acting simply by virtue of their weight are arranged above the petrol filter 65 in the pump body, whilst the suction valve 12 is in proximity to the upper extremity of the petrol inlet tube 6.

The pump body communicates with the suction chamber 15 through a pipe 16 which 70 terminates between the valves 12 and 13.

A perforated socket 17, with a fastening cap 18 is screwed to the top of the pump body 3 and places said pump body in communication through the pipe 19 with a pipe 75 20 which delivers the petrol to the carburetor.

The pump 20 is common to the two diaphragm pumps 1 and 2.

The casing 4 which contains the mechanism is common to the two pumps 1 and 2 and carries two plates 23 in each of which slides a piston 24.

Devices for filling, such as screwed stoppers 100¹, 100², are provided in said casing 85 and make it possible to constantly maintain the same filled with lubricant. Consequently the diaphragms 5, 5¹ of the two twin pumps keep between them a constant quantity of lubricant, which thus forms a liquid pad between the two diaphragms and prevents them from being torn.

Each piston 24 is fixed by a bolt 25 in the centre of the corresponding deformable diaphragms 5, 5¹. Said piston 24 is provided 95 with a plunger 40 which a spring 41 keeps away from the body of the piston itself and constantly pushes it into engagement with the driving cam 27.

The two pistons 24 are joined together by 100 a web 26 within which is lodged the rotary cam 27 forming an integral part of the driving shaft 28.

The pump is also provided with a safety device to prevent any excessive pressure in 105 the pump body. This device consists of an auxiliary diaphragm 101 mounted in the pump body 2 and in contact by its internal

face with the inner chamber 15 of the pump body.

The auxiliary diaphragm 101 is fixed on a shaft 103 by means of a nut 104 and a lock nut 105 screwed on said threaded shaft and securing the diaphragm 101 between two washers 106 and 107 placed on each side of said diaphragm.

The shaft 103 carries a push ring 108 which is kept in position on said shaft by an adjustable nut 109 and a lock nut 110.

A coil spring 111 is interposed between the ring 108 and an adjustable screw 112 provided with a lock nut 113.

15 The pump above described normally works in the following manner:—The cam 27, by rotating in the direction of the arrow 35, pushes the plunger 40 which, by means of the spring 41, pushes the piston 24 of pump 1. Said piston is displaced in the direction of arrow 36 and carries with it the diaphragm 5 which determines a depression in the suction chamber 15. The valve 12 rises, the petrol is sucked up into 20 the pump body 3, enters the same through the inlet tube 6, passes through the orifices of said tube 7, traverses the chamois leather 10, where it is cleared of its impurities, passes through the lifted valve 12 and fills 25 up the chamber 15.

When the cam, whilst continuing to rotate in the direction of the arrow 35, pushes back the piston 24 in the opposite direction to the arrow 36 the deformable diaphragm 35 5 drives the petrol in the chamber 15. The petrol raises the delivery valve 13, passes through the orifices in the socket 17, follows the pipe 19 and flows through 20 into the carburettor.

40 The two pumps 1 and 2 work in opposite directions to each other under the influence of the single cam 27, that is to say, that one of the pumps sucks up, when the other delivers or vice versa.

45 The two diaphragms 5, 5¹ of the twin pumps 1 and 2 are made dependent upon each other by the cross-piece or web 26 in such manner that the effects of atmospheric pressure or any other pressure acting on the 50 opposite faces of these diaphragms respectively in the direction P¹, P² neutralize one another. Consequently the displacements of said diaphragm are now only a function of the displacements of the driving parts 27 55 and of the pressures of the distributed liquid. A constant supply or a constant pressure or both these conditions at the same time are obtained whatever may be the variations in the atmospheric pressure, and consequently whatever may be the altitudes reached by the aircraft, if the pump feeds the explosion motors of such aircraft.

60 The arrangement thus automatically ensures a barometric or altimetric compensation.

The auxiliary diaphragm 101 represents another safety device assuring similar advantages.

Under normal working, the principal diaphragm 5, 5¹ under the influence of piston 70 24 receives to and fro motions in the direction 36 and in the opposite direction. These motions determine in the usual way variations in the capacity of the chamber 15 and consequently a suction of petrol through the 75 valve 12 and the delivery of said petrol through the valve 13 into the utilization pipe towards the carburettor.

Under normal working, the pressure in the chamber 15 is too weak to effect the compression of the spring 111. Consequently the auxiliary diaphragm 101 forms a nearly rigid wall and allows the variations in volume of the chamber 15 and the regular working of the pump.

80 On the contrary, if the pressure in the chamber 15 tends to become too high owing, for instance, to the delivery valve 13 being blocked, the spring 111 will become compressed and the auxiliary diaphragm 101 follows exactly the displacement of the principal diaphragm 5, 5¹. Consequently the 85 volume of liquid contained in the chamber 15 between the two flexible diaphragms 5, 5¹, and 101 remains constant. No further suction of petrol takes place through the valve 12 and the pressure in the chamber 15 can no longer increase or cause the breaking of the principal diaphragm 5, 5¹.

90 The tension of the spring 111 can also be regulated, as desired, by turning more or less the adjustable screw 112. The pressure in the chamber 15, under which the spring 111 becomes compressed, is thus regulated and the auxiliary diaphragm 101 is allowed to follow the displacements of the principal diaphragm 5, 5¹.

95 The nut 109 allows the course of the auxiliary diaphragm 101 being so regulated that said course should not be greater than that of the diaphragm 5, 5¹ in the direction of the arrow 36.

100 Numerous modifications may be introduced in the arrangement above described; the spring 111 in particular may be replaced by any other means to maintain the auxiliary diaphragm 101 stretched, in the case of normal pressure in the chamber and then yielding and allowing said diaphragm to relax and follow the motions of the diaphragm 5, 5¹ if said pressure tends to become too high.

I claim:

1. In a feed pump, the following combination: a pump body; a suction valve and a delivery valve mounted in said pump body; a main diaphragm mounted in said pump body; a driving member controlling said diaphragm; an auxiliary diaphragm mounted in said pump body; and means exerting pres. 125

sure on the auxiliary diaphragm and maintaining it stretched as long as the pressure in the pump body remains below a determined value, said means being arranged to 5 yield as soon as this pressure acquires an excessive value, the auxiliary diaphragm then following the main diaphragm in its displacements which prevents any variation in volume of the pump body chamber and 10 arrests the working of the pump.

2. In a feed pump, the following combination: a pump body; a suction valve and a delivery valve mounted in said pump body; a main diaphragm mounted in said pump 15 body; a driving member controlling said diaphragm; an auxiliary diaphragm mounted in said pump body; and yieldable means exerting pressure on the auxiliary diaphragm and maintaining it stretched as long as the 20 pressure in the pump body remains below a determined value, said means yielding as soon as the pressure acquires an excessive value, said auxiliary diaphragm then following the main diaphragm in its displacements which prevents any variation in volume 25 in the pump body chamber and arrests the working of the pump.

3. In a feed pump, the following combination: a pump body; a suction valve and a 30 delivery valve mounted in said pump body; a main diaphragm mounted in said pump body; a driving member controlling said diaphragm; an auxiliary diaphragm mounted in said pump body; means for exerting 35 pressure on said auxiliary diaphragm and

maintaining it stretched as long as the pressure in the pump body remains below a determined value, said means yielding as soon as this pressure acquires an excessive value, the auxiliary diaphragm then following the main diaphragm in its displacements, which prevents any variation of volume in the pump body chamber and arrests the working 40 of the pump; and regulating elements for adjusting said auxiliary diaphragm pressure 45 means.

4. In a feed pump, the following combination: a pump body; a suction valve and a delivery valve mounted in said pump body; a main diaphragm mounted in said pump 50 body; a driving member controlling said diaphragm; an auxiliary diaphragm mounted in said pump body; means for exerting pressure on said auxiliary diaphragm and maintaining it stretched as long as the pressure in the pump body chamber remains below a determined value, said means yielding as soon as the pressure acquires an excessive value, the auxiliary diaphragm then following said main diaphragm in its displacements which prevents any variation of volume 55 in the pump body chamber and arrests the working of the pump; and abutment elements connected in an adjustable manner with said auxiliary diaphragm and permitting regulation of the extent of movement 60 thereof.

In testimony whereof I affix my signature.

ALEXANDRE LAMBLIN.
